METHOD OF MENDING BURLAP BAGS

George I. Goldwyn, Chicago, Ill.

Application May 25, 1933, Serial No. 672,782

3 Claims. (Cl. 112—262)

This invention relates to improvements in methods of mending burlap bags, and it consists of the matters hereinafter described and more particularly pointed out in the appended claims. 5 The present application is a continuation, at least in part, of my copending application, Serial No. 581,821 filed December 18, 1931.

Heretofore used burlap bags and especially those having holes torn or worn therein, were 10 considered as waste. Large establishments have grown up making a specialty of reconditioning such bags for further use, by cleaning and patching such bags.

Burlap bagging is a relatively loose woven 15 fabric of jute and the ends of the warp and weft threads thereof, at the edges of a hole or patch, tend to slough off as lint. When a patch is applied to such a hole and is secured thereto by a line of stitching, this line of stitching must be spaced well from the edge of the hole and 20 well within the edges of the patch, otherwise, the stitches tend to pull through the bagging or patch when the bag is again used. It is apparent that such a patched bag must present a 25 somewhat unsightly appearance and is no stronger than the stitching employed to secure the patch in place. Therefore, a so-called patched bag is only used for the lower grades of merchandise.

30 The primary object of the present invention, is to provide an improved method of mending burlap bags, whereby the mend is much stronger than the bag material itself and is not only substantially invisible but may be made in less time 35 than it takes to apply a patch, so that the mended bag in all appearances, is hardly recognizable as a reconditioned used bag.

Another object of the invention is to provide 40 a method of mending used bags which is practical in commercial use in that it can be carried out by power driven, industrial sewing machines, wherein a plurality of needle threads are employed in connection with a single bobbin thread, and which threads form a lock-stitch, a line 45 of which is first run around the hole and then back and forth in all directions, providing a mend of network character, wherein the multiple thread stitches are interlocked or interwoven with each other and with the margin of the 50 bag material about the hole or worn spot to provide a mend of a finer and stronger weave than the bag material itself.

Still another object of the invention is to provide 55 a machine by which the improved method may be readily carried out.

The above mentioned objects of the invention, as well as others, together with the many advantages thereof, will more fully appear as I proceed with my specification.

In the drawings:

Fig. 1 is a perspective view of a burlap bag, 5 mended in accordance with my improved method;

Fig. 2 is a view in elevation of a portion of a burlap bag having a hole therein and illustrates 10 certain of the first steps in the mending of said hole;

Fig. 3 is a view similar to Fig. 1, illustrating further steps in the mending of the bag;

Fig. 4 is a perspective view on an enlarged 15 scale of the preferred form of stitching employed in my improved method of mending burlap bags.

Fig. 5 is a perspective view of the needle bar head and associated bed plate parts of a machine by which the improved method may be 20 carried out, with the presser foot thereof down and the needle bar up to better show the disposition of the needles;

Fig. 6 is a detail sectional view through a 25 part of the machine on an enlarged scale as taken on the line 6—6 of Fig. 5 and shows more particularly the position of the shuttle when the needle bar is in its up position;

Fig. 7 is a view similar to Fig. 6 with the parts 30 in a changed relation; and

Fig. 8 is a perspective view on an enlarged scale of a conventional sewing machine needle.

In general, my improved method of mending burlap bags is best carried out with the aid of an industrial sewing machine employing a single 35 bobbin thread and two needle threads connected together as a lock stitch. Such a machine is preferably of the oscillating shuttle type and the needles are disposed in relatively close tandem fashion, in front of and behind the axis of the 40 associated needle bar.

The eye in the front needle is arranged at an elevation below that of the eye in the rear needle.

The hook of the shuttle in the oscillation of the latter moves upwardly from the rear and 45 clockwise toward the operator, in its needle thread loops engaging position just after the needles start their ascent. Thereafter the hook moves in the other direction away from the operator to complete the stitch. By arranging the eye of 50 the front needle at a lower elevation, this provides the time element necessary to insure that the thread loop of the front needle be in proper position to receive the shuttle hook as it passes from the rear needle toward the front needle.

The machine is provided with a peculiarly shaped presser foot having a rounded bottom to eliminate all corners or edges and furthermore, as the bag being mended is manually fed back and forth and laterally in both directions, the machine is devoid of the conventional or other type of feed dog.

Should only a single needle thread be employed in connection with a single bobbin thread in making a mend, in the shifting of the bag fabric beneath the presser-foot, the tendency is to pull the thread from the needle with the result that longer and looser stitches are formed, and these stitches being under different tensions, will invariably pucker.

Both needle threads and the bobbin thread must be much finer than the warp and weft threads of the bag material, but should be of cotton or linen (preferably the former, due to cost) of a color approximating as close as practical that of the bag material, which is substantially a straw color.

Such a thread is much stronger than the warp and weft threads of the bag fabric or material and permits of use of finer needles which may be run at great speed. Again, such finer threads will not lint, and feed easier through the needles without breakage, and with the finer needles, the tendency to needle-cut other threads already in the mend, is avoided, as the needles will more readily pass between such threads, than through said threads. When that part of the bag material having the hole or worn spot therein, is passed back and forth in all directions beneath the presser foot, a base net-work, web or weave of interconnected triple thread stitch is produced. In the further movement of the bag material, the interstices between the basic net-work or web of stitches are gradually closed up until the mend is completed, which completed mend is flat, even and non-puckery and substantially defies detection and is indeed much stronger than the bag material itself.

Referring now in detail to that embodiment of the invention, illustrated in the drawings:

1 indicates as a whole a burlap bag made from a piece of burlap of the desired area folded upon itself to provide the two walls 2-2 of the bag stitched along one side margin and end to provide the bag, open at one end. In the rough handling to which burlap bags are subjected in use, holes and thin worn spots or areas of different sizes and shapes develop. In Fig. 2 one of such holes is indicated at 3.

For carrying out the method, I have produced an improved sewing machine arrangement such as shown in Figs. 5, 6 and 7 and capable of using two needle threads 4-4 and a single bobbin thread 5, all of said threads cooperating to form a lock stitch.

This arrangement is more particularly concerned with the presser foot, needle and shuttle mechanism, all other parts of the machine being of conventional form. In making the mend, as the bag is moved manually in all directions in a horizontal plane forwardly and rearwardly as well as sidewise with respect to the plane of the needles, the feed dog is eliminated as unnecessary.

As shown in the drawings, 6 indicates the bed plate of the sewing machine and 7 indicates the usual head on the end of the overhanging arm 8. Vertically disposed in said head is a presser foot bar 9, that carries a presser foot 10 at its bottom end. This presser foot which is substantially

crescent shaped, is curved from front to rear and has upturned side flanges 11 so as to present a smooth rounded bottom to the bag fabric in its movement in the various directions manually imparted thereto. A lever 12 is provided at the rear of the head whereby the presser foot may be lowered into and raised out of operative engagement with respect to a shuttle covering plate 13 removably secured in the bed plate. In Fig. 5, an opening is shown in the bed plate towards its end, which opening is closed by a suitable cover when the machine is being operated.

14 indicates a vertically reciprocating needle bar suitably arranged in the head. The bottom end of said bar carries a clamp 15 to receive in tandem fashion, front and rear needles 16 and 17 respectively. Each needle which is generally of the conventional type as shown in Fig. 8 has a piercing point 18 at its bottom extremity and an eye 19 a suitable distance above the same. In one side of the shank of the needle is a thread groove 20 which opens into one end of the eye. The bottom end of the other side of the shank is a cutaway, as at 21, to accommodate the shuttle hook in its stitch forming movement past the needle.

Below the plate 13 in the bed plate is located a shuttle 22 that is mounted in the conventional manner in a shuttle race and which shuttle is oscillated in its race about a horizontal axis, disposed longitudinally of the bed plate. The shuttle substantially surrounds the usual case 24 which encloses the bobbin 23 for the thread 5 and this shuttle includes a pointed hook 22a.

It is apparent that in the oscillation of the shuttle in its race the point of its hook, travels back and forth in a path concentric with its axis and preferably this axis is located in the plane of the needle bar. As the needles are disposed in planes in front of and behind of the axis of the needle bar, said needles are so set that the eye of the front needle is disposed at an elevation below that of the eye of the rear needle. This difference in eye elevation may be accomplished in two different ways. One needle may be of a greater length than the other so that when fully inserted into the front socket in the clamp, its eye is disposed at the lower elevation. Again, both needles may be identical. With such needles, the front one is set further down in the clamp.

In the operation of the machine, the needles on their descent pass through the fabric of a bag wall 2 and carry their respective threads 4-4 therethrough. In the initial part of their ascent, a thread loop is formed in each needle thread between its eye and the bag wall. In each clockwise part of the movement of the shuttle as viewed in Fig. 7, its hook passes through both needle thread loops and then moves counterclockwise.

While the needle bar and shuttle movement is extremely fast, the relative elevated positioning of the eyes in the needle provides a lag in the loop formation of both needles. This insures the presence of a loop in the thread of the front needle for the shuttle hook to go through after passing through the loop of the thread of the rear needle.

This arrangement is quite important because with the needles offset in tandem fashion, the shuttle hook as it passes through the thread loop of the rear needle is moving clockwise and upwardly toward the perpendicular plane of its axis and after passing said plane, it is moving down-

wardly. It is apparent that if the front needle thread loop was not in a position to receive the hook, the hook could not coact with the front needle in the making of a lock stitch having the two needle or upper threads and the single bobbin or under thread.

As is apparent from Fig. 5, the machine is provided with the usual tensioning and feed devices. These devices are so formed as to individualize each thread from its own supply spool to the associated needle. With this arrangement, tangling of the threads is avoided.

In mending a hole in a bag 1 that part of the bag wall having the hole therein is positioned upon the bed plate of the machine from its end, under the presser foot. If an area of the bag has been worn thin and it is desired to reinforce the same, this area would be operated upon in the same manner. In thus positioning said bag wall part, the operator grasps said bag part with both hands and somewhat tightening or stretching the material in a plane laterally and to both sides of the presser foot 10 with the result that under the stretch of said material in the mending of a hole, the hole takes on a rather elongated shape, as shown in Fig. 2. An outline stitch 25 is then run around the hole at a suitable distance therefrom and when such an outline stitch has been finished and without breaking the threads, it is continued back and forth across the hole in the plane of its shortest dimension beginning from one end thereof as best shown at 26 in Fig. 2.

This is carried out by moving the bag wall toward and away from the operator and at the same time employing a lateral movement so that said stitches zig zag across the hole. When the other end of said hole has been reached, the bag is moved laterally back and forth so that the lines 27 of stitches are zig zagged lengthwise of the hole. It is desirable that the turns 28 of said lines of stitches all be made in that part of the bag fabric within the outline stitch, which acts as a sort of visible guide within which the other stitches should be kept. Should the zig zag stitches run beyond the outline stitch no particular harm results. In laying in the stitches mentioned, those lines of stitching running lengthwise of the hole, of course, cross or intersect those running in the other direction and at said intersections, both lines of stitches are in themselves interlocked to provide a net or web-like base as best shown in Fig. 3.

Thereafter, the bag is moved back and forth in any direction as happens to suit the operator's fancy, until the lines of stitching thus laid in intersect with companion lines of stitches to fill up the interstices in the web-like base. This laying in of the lines of stitchings is continued until the entire area of the holes or worn spot is covered to finish the mend.

The mend thus made constitutes crossing and recrossing lines of triple thread stitches with the needle or upper threads arranged side by side.

These triple thread stitches are interconnected with each other throughout the entire area within the outline stitch with a stitch-like weave which has a resistance to wearing and tearing strains greater than that of the surrounding bag material.

Thus with a plurality of needle threads and only a single bobbin thread, a much stronger and flatter mend is produced over the use of a single needle thread and single bobbin thread and coverage is increased with resulting benefits.

While in describing the invention, I have referred in detail to a certain sequence in the steps employed in the improved method but this is to be considered merely as illustrative so that I do not wish to be limited thereto except as may be specifically set forth in the appended claims.

I claim as my invention:

1. In combination with the desired area of burlap bagging having relatively coarse warp and weft threads, a mend therefor, comprising a plurality of closely adjacent lines of lock stitching extending back and forth across said area and including a bobbin thread locking at least two needle threads laid side by side, said lines of stitching passing not only through certain threads of the bagging but also through each other so as to connect said lines of stitching to said bagging and to each other.

2. A method of mending burlap bagging having relative coarse warp and weft threads on a machine having a plurality of parallel needles cooperating with a single bobbin, said method comprising forming adjacent lines of lock stitching back and forth across a desired area in said bagging having a hole therein, and which lock stitching includes a plurality of needle threads arranged substantially side by side and a single bobbin thread locking at least two needle threads together, and then moving the bagging back and forth relative to the plane of the axes of the needles carrying the needle threads in directions other than that in the line of said plane and thereby completing said mend.

3. The method of mending burlap bagging on a machine having a plurality of parallel needles cooperating with a single bobbin, said method comprising forming adjacent lines of lock stitching across a desired area in said bagging having a hole therein, the lock stitching including a pair of needle threads, and a single bobbin thread that locks said two needle threads together, said needle threads being arranged substantially side by side, and then moving the bagging relative to the plane of the axes of the two needles carrying the needle threads in directions other than that in the line of said plane so as to pass the various lines of stitching through the warp and weft of the bagging as well as through each other to form a mending weave of interconnected lines of such stitching.

GEORGE I. GOLDWYN.
